SUSTAINING ROTOR FOR AIRCRAFT

Paul H. Stanley, Huntingdon Valley, Pa., assignor to Autogiro Company of America, Willow Grove, Pa., a corporation of Delaware

Application February 9, 1940, Serial No. 318,041

1 Claim. (Cl. 244—17)

This invention relates to sustaining rotors for aircraft, and is more particularly concerned with features of rotor blade construction, as fully described hereinafter.

Sustaining rotor blades are commonly constructed in such manner that at least a large portion of the interior of the blade is hollow. Such blades, moreover, are of substantial length, for instance from about 15 to about 25 feet, and rotate at a relatively high rate, for example from 150 to 300 R. P. M.; and in the upper portion of the range of rotor speeds blade failures have been known to occur, for instance by tearing or rupturing of the external contour-defining material of the blade, the cause of which was not apparent.

I have found that when such a blade is rotated, at high speed, pressures substantially above atmospheric are built up in the outer portion of the blade, especially at the tip, as a result of the action of centrifugal force on the body or column of air within the blade, and I have further discovered that this built-up of pressure was responsible for such failure of the blade covering adjacent the tip end, and also in other cases for distortion of the sectional contour of the blade, especially toward the tip.

The present invention has in view overcoming the above difficulties. This is accomplished in accordance with the invention by providing a vent or aperture in the blade covering in the outboard portion of the blade and preferably adjacent the tip. At the same time the invention contemplates substantial sealing of the inboard end of the blade to prevent ingress of air to its interior, from that end.

How the foregoing is accomplished, together with other objects and advantages, will be more apparent from the following description, referring to the accompanying drawing, in which—

Figure 1 is an outline perspective view of the underside of a rotor blade constructed in accordance with the invention;

Figure 2 is a fragmentary enlarged sectional view of the blade of Figure 1 taken in the region of the blade tip; and

Figure 3 is a longitudinal sectional view through the inner end of the blade spar and the associated root end fitting.

While the invention is applicable to blades of a variety of different types of construction and may be applied to any aircraft sustaining rotor blade having an internal hollow of substantial dimension lengthwise of the blade, for purposes of illustration the invention is shown in the draw-

ing as applied to a blade of the type built up on a single spar, constituting the primary longitudinal structural element, the spar carrying a multiplicity of spaced ribs which, in turn, support sheet material, such as fabric, for defining the blade contour.

In Figure 1 the blade spar is indicated at 4, this spar being telescoped at its root end with a fitting 5 having spaced apertured lugs 6—6 adapted to cooperate with a mounting pivot, by means of which the blade is connected with the hub with freedom for swinging movement under the influence of flight forces. Any desired number and arrangement of pivots may, of course, be adopted, preferably including at least a "flapping" pivot providing freedom for swinging movement of the blade in a direction generally transverse its mean rotative path of travel, and a "drag" pivot providing for swinging movement of the blade generally within its mean path of travel. As shown in the drawing, the apertured lugs 6—6 are adapted to cooperate with a pivot of the latter type.

At intervals along the spar, a plurality of transverse ribs 7 are provided defining a skeleton of the desired blade section and plan form. The trailing edges of the several ribs may be joined, if desired, by the trailing edge stringer 8 (see Figure 2). In the region of both the root and tip end portions of the blade, and also along the nose portion, the blade is preferably covered with plywood 9, and then fabric 10 is applied over the entire blade structure, the fabric being doped in accordance with accepted practice. A blade structure of the general type referred to just above is more fully disclosed in copending application of Agnew E. Larsen and myself, Serial No. 309,586, filed December 16, 1939.

In blades constructed as above, the ribs 7 are quite commonly apertured, as indicated at 11 in Figure 2, so that all portions of the interior of the blade lengthwise thereof are in communication with each other. Even where the ribs are not so apertured, it will be apparent that substantial communication from end to end of the blade is usually present by virtue of clearance between the ribs and the spar where the latter passes through the ribs, and at various points between the fabric and the ribs. In such a blade, for example of a length of about 20 feet and at a rotational speed of from 200 to 300 R. P. M., the internal pressure at the tip has been found to rise as high as 3.5 pounds per square inch above atmospheric. This is sufficiently high to distort the blade contour by bulging of the fabric

and even of plywood and sheet metal coverings adjacent the blade tip, and actually to rupture the blade, especially in those regions of the blade profile where the external pressure is reduced below atmospheric by the aerodynamic effects during operation of the blade.

With the foregoing in mind, in accordance with the present invention, a vent aperture 12 is provided, preferably adjacent the tip of the blade and on the underside thereof, closer to the trailing edge than to the leading edge. In addition to its positive functional advantages, location of the vent on the lower side of the blade tends to prevent entrance of rain, etc. Positioning the vent nearer to the trailing edge than to the leading edge is of advantage since in this region the positive aerodynamic pressure is lower and more closely corresponds to normal atmospheric pressure than in regions further forward on the blade. The area surrounding the aperture or vent may be reinforced as by a washer 13 which may be secured in place in any convenient way, and over the edge of which the fabric covering is preferably extended as indicated at 14, the latter being doped to the washer.

The aperture 12 provides for venting of the air from the interior of the blade and thereby results in substantial equalization of the internal and external pressures during rotation. It also, of course, permits ingress of air, when the rotor slows down, to balance the static condition.

At the same time, the invention contemplates substantial sealing of the inner end of the blade covering around the spar 4 or the blade root fitting 5. This may be accomplished by use of an inner end closure rib or the like 15 having a tight fit or some sealing means applied around the root end fitting 5, and to which the adjacent edges of the fabric are carefully doped. Care should also be taken in fabrication of the blade to make sure that the fabric throughout all of the inboard portion of the blade is carefully applied and doped in place so as to prevent ingress of air under the action of centrifugal force during rotation of the rotor.

By the foregoing means provision is made for venting the interior blade hollow adjacent the outer end of the blade, and continuous circulation of air lengthwise through the blade and out of the vent is at the same time prevented. If this circulation or "pumping" action takes place (as it would in the event of a substantial aperture in an

inboard portion of the blade) certain undesirable pressure conditions are likely to be set up in the outboard portion of the blade notwithstanding the presence of the vent.

5 With this latter point in mind, I prefer also to plug or otherwise close the inner end of the spar 4, as indicated at 16 in Figure 3. Any suitable light plug, such as a cork, may serve this purpose, and thereby flow of air outwardly through the 10 spar and into the tip of the blade, under the influence of centrifugal force, is prevented.

I have found that with a blade of the length and rotational speed mentioned above, a vent opening of about $\frac{3}{8}$ " diameter will reduce the 15 internal pressure sufficiently to avoid substantial distortion and eliminate danger of failure, provided such opening is located within about the outer one-third of the blade length. As indicated above, however, the vent is preferably 20 placed closely adjacent to the tip, although care must be taken not to locate the vent outboard of any imperforate rib which is so tightly sealed with the spar and the blade covering as to impair the venting of air from the remainder of the 25 blade.

It will be apparent that the invention is also 30 applicable to metal or plastic blades of similar or other skeleton structure, so long as an interior hollow is present of substantial dimension lengthwise of the blade.

I claim:

For an aircraft sustaining rotor, an elongated blade of airfoil section comprising a longitudinally extending strength structure for mounting 35 the blade and sheet material carried thereby and defining the airfoil contour of the blade and further defining an internal hollow extended longitudinally of the blade throughout at least a major portion of the length of the blade, and the 40 sheet material being subject to possible deformation or rupture upon substantial build-up of air pressure in said hollow by the centrifugal force of high speed rotation of the blade, an outer end portion of said hollow having venting means 45 adapted to relieve air pressure therein built up by the centrifugal force of rotation, and the inner end portion of said hollow being sufficiently sealed to avoid build-up of a pressure sufficiently to materially distort the airfoil section or to rupture 50 the blade despite the venting.

PAUL H. STANLEY.
